CLAIM

The ornamental design for an exercise bar, as shown and described.

DESCRIPTION

FIG. 1 is a first perspective view of the exercise bar of Applicant's invention.

FIG. 2 is a second perspective view of the exercise bar of Applicant's invention.

FIG. 3 is a third perspective view of the exercise bar of Applicant's invention.

FIG. 4 is a top view of the exercise bar of Applicant's invention.

FIG. 5 is a bottom elevation view of the exercise bar of Applicant's invention.

FIG. 6 is a front view of the exercise bar of Applicant's invention.

FIG. 7 is a back elevation view of the exercise bar of Applicant's invention; and,

FIG. 8 is a right view of the exercise bar of Applicant's invention.

The broken line showing of weight plates in FIG. 1 depicts environment and forms no part of the claim.

1 Claim, 5 Drawing Sheets
